SUCTION CLEANER

George A. Brace, Highland Park, Ill., assignor to The Hoover Company, North Canton, Ohio, a corporation of Ohio

Application October 21, 1953, Serial No. 387,423

19 Claims. (Cl. 183—51)

The present invention relates to suction cleaners and more particularly to a novel tank type cleaner construction having an improved and simplified throw-away paper filter and a new mode of mounting the same within the cleaner.

One of the prime objectives of this invention is to simplify and improve the means for mounting and coupling an inexpensive throw-away paper filter bag in a suction cleaner in a manner avoiding the use of complex and ineffective coupling devices heretofore proposed. The present coupling is designed for use with filters having inlets no larger than required to accommodate the incoming air stream thereby greatly minimizing the possibility of dirt escaping from the filter during its removal. It is also the purpose of the invention to provide an exceedingly simple resilient self-expanding filter coupling which grips the edge of the filter inlet automatically and in an airtight manner as it is allowed to expand after insertion into the filter opening. By the same token, my novel coupling is readily detachable merely by collapsing its side wall inwardly to greatly reduce its cross sectional area thereby facilitating withdrawal from the filter opening. This coupling may be mounted directly on or separately from the filter chamber access cover. In either arrangement the same unitary coupling is employed to make an airtight joint with the filter as well as with the usual suction hose.

Another feature of the invention involves the provision of a collapsing paper filter which is completely closed except for a small inlet opening and, in consequence, is designed for a single filling of dirt after which it is thrown away and replaced by a new bag.

Numerous other features and objectives will become apparent from the following detailed specification of illustrative embodiments taken in connection with the accompanying drawings, wherein:

Figure 1 is a vertical sectional view through a canister type suction cleaner incorporating the invention according to a preferred embodiment thereof and showing the newly installed filter bag in place therein;

Figure 2 is a fragmentary view through the filter chamber end cap and showing the latter, as well as the filter coupling, pivoted outwardly away from the filter chamber;

Figure 3 is taken along the plane 3—3 on Figure 1;

Figure 4 is a fragmentary sectional view showing manually operable means for collapsing the filter coupling;

Figure 5 is a vertical sectional view through the filter chamber of another embodiment showing a filter bag clamped in position therein and the end cap approaching closed position; and

Figure 6 is a fragmentary sectional view of still another embodiment showing the filter bag in expanded condition and the suction hose coupled in place on the cleaner.

Referring now to Figures 1 to 3, it will be seen that the invention is shown incorporated in a tank cleaner having an elongated cylindrical casing 10 open at its

2

opposite ends and supported on a pair of runners 11 in accordance with conventional practice. The rear end of the casing is closed by an end cap 12 secured thereto as by screws 13 and having a combined air discharge opening and blower hose coupling facility 14. A multiple stage unitary motor-fan unit generally designated 15 is supported horizontally within the rear end of the casing. Preferably, this unit is cradled in a pair of resilient gaskets 16 and 17 supported respectively in a spider diaphragm plate 18 and an annular ring 19. The former is provided with a number of air outlet openings 20 through which the air flows on the way to the discharge opening 14. Annulus 19 has a large diameter central opening 21 which is normally covered by a porous final filter 22. The motor-fan unit includes a horizontal axis electric motor 23 directly coupled to a multiple stage suction fan 24 having an air inlet 25 at its forward end. The casing of fan 24 may be provided with peripheral air outlets, not shown, or the air may discharge axially through the motor to cool the same as it flows toward the discharge opening. The driving motor is controlled by a push-push snap switch 26 mounted on the upper side of the casing wall and controlled by a switch button 27 located at one end of the carrying handle 28.

The entire forward end of the cleaner casing forms a filter chamber 29 normally closed by an end cap 30 pivotally connected to the lower edge of the opening as by hinge 31. The cover is provided with a female hose socket 32 to which the usual suction hose may be detachably connected in a well known manner.

As best shown in Figure 3, the cleaner casing is of rounded rectangular shape in cross section. Secured to the inner side wall adjacent the inlet end of the casing is a flanged ring 33 against which a resilient sealing gasket 34 carried by the end cap seats when the end cap is closed. A toggle clamp 35 carried by the top of the casing engages with a detent 36 on the rim of the end cap to lock the latter in closed position.

My novel filter clamp or coupling comprises a soft rubber frusto-conical ring generally designated 37 having a flange 38 projecting from its underside. The coupling member is cradled in a semi-circular notch 39 formed in the upper edge of a plate 40 hinged at 41 to the lower inlet edge of the filter chamber. As clearly shown by Figures 2 and 3, plate 40 covers the lower half of the filter chamber inlet and its opposite side edges seat against depressed channels 42 formed in the inturned rim of ring 33. The filter coupling 37 is secured in place in cut-out 39 by means of rivets or the like 43 passing through flange 38.

The smaller innermost end of the coupling has a low radially projecting annular ring or flange 44 adapted to seat against the inner rim of the filter bag inlet. Projecting radially from the sides of the coupling are a series of ribs or fins 45, the innermost edges 46 of which slope downwardly to a point spaced slightly rearward of annular flange 44. Thus, the base of the inner ends of fins 45 cooperate with the adjacent wall of flange 44 to form a narrow groove or seat 47 for the edge of the filter inlet. Normally, of course, the coupling 37 occupies the circular expanded position represented by the full lines in Figure 3.

However, it is readily collapsible so as to occupy a smaller cross section merely by applying radial pressure downwardly from the top wall thereof—as represented by the dotted line in Figure 3. When so collapsed, it will be readily apparent that the inner end can be easily inserted through the inlet opening of a filter bag.

One type of a simple throw-away paper filter bag is shown in Figures 1 to 3. Thus, the filter bag generally designated 48 comprises a tubular main body provided with inwardly folding pleats 49 on its opposite side for convenient handling and compact packaging. The inner-

most end of the main body is overturned and sealed closed as indicated at 50. The opposite end is formed like a conventional flat bottom grocery sack and is provided with an inlet opening 51 in the center thereof. If desired this opening may be reinforced as by a paper ring 52 glued to the bottom of the bag in registry with opening 51. Usually, however, such a reinforcing ring is not necessary since the bottom is formed by several layers of overlapping paper glued together to form an airtight closure for the bag. Opening 51 is preferably slightly smaller in diameter than the base of groove 47 in the resilient coupling 37. Accordingly, the expansion of this ring to its normal full diameter forces the base of groove 47 tightly against the inlet rim of the filter bag thereby providing an airtight seal. Flange 44 is then seated tightly against the inner rim of the filter opening and the cammed lower edges 46 of ribs 45.

Operation

Let it be assumed that the operator wishes to install a new filter bag in the cleaner. She first releases toggle 35 and opens the end cap downwardly against the floor. The filter bags, as manufactured, are folded flat with the bottom of the bag folded downwardly against the flattened body of the bag. The operator grasps the upper rim edge of the bottom and lifts or rotates it until the plane of the bottom lies normal to the flat main body of the bag. Thereafter, the operator inserts the filter downwardly into the filter chamber after first swinging plate 40 carrying the collapsible coupling outwardly for greater convenience in dropping the filter into the cleaner. The operator then places her index finger along the top side of the coupling and depresses it downwardly to the collapsed position shown by dotted lines in Figure 3. While it is held in this position, she guides the inner end of the collapsed coupling into inlet opening 51 of the filter bag. For greater convenience in guiding the coupling into the filter opening, the operator preferably places the lower edge of the filter bottom in the Y-shaped notch provided by bracket 53. As soon as groove 47 of the coupling lies in the plane of the filter inlet opening, the operator releases the pressure on the coupling allowing it to expand under its own resiliency and in so doing keeps the coupling pressed inwardly slightly so that the outer rim of the filter opening is guided into groove 47 by the cammed edges 46 of fins 45.

The end cap may now be swung to closed position and latched there by toggle 35. As the end cap closes, sealing gasket 34 bears against the opposite side edges of plate 40 and forces it into seating engagement in depressions 42 of ring 33. The frusto-conical walls 32 of the hose coupling also seat firmly against the inner walls of coupling 37 to form an airtight seal between the hose coupling and the filter coupling when the end cap is in closed position.

As soon as the motor-fan unit is energized the fan will draw air inwardly through coupling 32 and expand the filter bag to its fully inflated position. The usual cleaning hose and cleaning tools are coupled to socket 32 and the cleaner can then be used in a conventional manner to clean the floor, furniture, draperies and the like.

The removal of the dirt filled filter bag is accomplished in a very simple manner. Toggle 35 is first opened and the cover is swung to open position thereby releasing plate 40 so that it may be swung outwardly. The operator then places her index finger on the top of coupling 37 and depresses it as she grasps the top edge of the filter bottom with the other hand and withdraws it from the collapsed end of the coupling. A new filter is then re-installed in the cleaner in the same manner described above and the end cap is latched in closed position.

If preferred, coupling 37 may be provided with a manual operator for collapsing it of the type illustrated in Figure 4. The collapsible coupling 37' is substantially identical with that just described and is carried in a notch

39' of pivoting plate 40'. The manual collapsing means for the coupling comprises a loop of wire 55 encircling the coupling and having an operating handle slidably mounted on the outer wall of plane 40' by a clip 56.

5 The lower end 57 is bent upwardly and looped to form a finger piece by which loop 55 may be depressed downwardly toward the pivoted edge of the plate. The upper edge of loop 55 seats in notches 58 formed in ribs 45'.

From the foregoing, the operation of the manual operator will be quite apparent. Normally, of course, the resiliency of coupling 37' will hold loop 55 in the position illustrated. To collapse the coupling, the operator merely places her thumb or finger on finger piece 57 and pushes the same downwardly thereby collapsing the coupling. As soon as she releases her pressure on the finger piece, the resiliency of the coupling will cause it to expand to its normal diameter and return loop 55 and its attached finger piece to its normal position.

Second embodiment

The same or similar parts of another embodiment illustrated in Figure 5 are designated by the same reference characters used in describing Figure 1 except that they are distinguished by a single or a double prime. The 10 resilient self-expanding rubber coupling 37" differs in being generally cylindrical and in having its inner or discharge end cut off on the bias as clearly illustrated for greater convenience in connecting the coupling to an air inlet opening 51' formed in the flat side wall of the non-reusable paper filter bag 60. This filter bag is made in the same general manner as described in connection with the first embodiment except that the inlet opening is located in one of the flat side walls adjacent the end thereof opposite the flat bottom 61 of the filter. Inlet opening 51' may be and preferably is reinforced with a relatively 15 stiff plate 52' glued to the side wall of the bag and having a tab 62 projecting beyond the outermost end of the filter and forming a finger piece as a convenience to the operator in assembling and disassembling the filter on coupling 37".

As described previously, the collapsible coupling 37" is seated or cradled in a semi-circular notch formed in the top edge of a plate 40" hinged to the cleaner casing at 41'. Accordingly, it will be understood that the upper half of the coupling is freely accessible to the operator's fingers so that it can be collapsed downwardly against the lower wall of the coupling when assembling or disassembling the filter bag. The outer end of coupling 37" is flared outwardly at 63 and forms a seat 20 against which the inwardly flared ring 64 of the hose coupling 32' seats in an airtight manner when end cap 30' is locked in closed position.

It will be appreciated that since coupling 37" is cylindrical in cross section and is cut off on a bias, that the filter seating groove 47" is elliptical. Accordingly, filter 25 inlet opening 51' must be of a corresponding elliptical shape but is preferably slightly smaller in area for obvious reasons. In consequence, the expansion of the coupling to its normal shape and size results in the slight deformation of the edges of the filter inlet thereby assuring an airtight seal with the filter bag. The bias cut also provides a pilot of considerable assistance in guiding the coupling into the filter inlet.

The elliptically shaped opening in the filter bag also 30 gives assurance that the filter will always be assembled in the proper orientation within the filter chamber. This is of particular importance where the bag has an irregular cross section such as the trapezoidal shape clearly illustrated in Figure 3. From this figure it will be observed that the top edge of the filter bag is narrower than the bottom edge to correspond with the similar dimensions of the adjacent sides of the cleaner casing. Obviously, it would be undesirable to mount such a filter bag with the wider edge uppermost. Of course, where 35 the inlet opening is in the flat bottom of the filter, as it is

in the first described embodiment, it is quite apparent to the operator that the bag should be so oriented as to correspond to the shape of the casing before it is inserted into the filter chamber. However, this relationship is not so readily apparent when the inlet is located in the side wall of the bag as it is in the Figure 5 embodiment.

After the filter has been assembled to the inner end of the resilient coupling, the end cap is swung to closed position so that in-turned flange 64 seats tightly against the out-turned flange 63 on the outer end of the coupling. At the same time, gasket 34' seats against ring 33' to form a seal at this point. Toggle clamp 35' is then closed against detent 36' to lock the cover closed. The manner of removing the filter when filled with dirt will be self-apparent from the foregoing and therefore need not be further described.

Third embodiment

Still another embodiment of the invention is illustrated in Figure 6 wherein the same or similar parts are designated by the same numerals as in the other views but are distinguished by double or triple primes. This embodiment differs from the other arrangements in that the collapsible rubber coupling 37''' is carried by a plate 65 secured directly to end cap 30''' as by screws 66 and, in fact, forms the inner wall of the end cap. The coupling is held firmly in place on wall 65 by means of annular ribs 67 projecting radially from the body of the coupling. Although the coupling member is not shown as provided with fins 45, it will be obvious that these may be present to assist in guiding the filter inlet into position in the seating and sealing groove 47''''. The non-reusable paper filter bag 48' is shown in an inflated condition in Figure 6 and the filter inlet 51''' located centrally of the flat bottom of the bag in reinforced by a stiff paper collar 52''' glued or stitched in place.

It will be quite apparent that it is not possible for the operator to collapse the coupling with her finger as in the other embodiments. Instead, an L-shaped manually operated collapsing means 70 is reciprocably mounted on the end cap. The shorter leg 71 extends through an opening in flanges 67 along the top side of the coupling. The longer leg extends through an opening in a supporting bracket 72 and through another opening in a depressed wall portion 73 of the end cap. The compression spring 74 surrounds the longer leg. One end bears against bracket 72 while the other end bears against a collar 75 anchored to rod 70. A suitable thumb piece 76 is mounted on the end of the rod in a convenient position to be contacted by the operator's thumb or finger. Normally, of course, the spring holds the manual operator in the position shown which corresponds to the normal expanded position of coupling 37'''.

The suction hose 77 carries a hollow male coupling tube 78 which extends through and seats in the coupling socket 32''' carried by the end cap. The innermost end of this tube extends into the interior of coupling 37''' in an airtight fit which is facilitated by the tapered inner end of the tube. Tube 78 is locked in place by a spring detent 79 which engages a shoulder carried by the hose socket. A button 80 serves to depress latch 79 to unlock the hose when it is desired to remove it. Note that the outermost end of coupling 37''' terminates close to but spaced from the inner end of coupling socket 32''''. Accordingly, the flexible coupling is free to be collapsed without interference from the hose socket.

To remove the filter bag, the operator releases the toggle latch 35''' and swings the cover partially toward open position after first detaching hose 77 from the end cap. She then depresses the manual operator by pressing downwardly on thumb piece 76 causing shorter leg 71 to collapse the top wall of the coupling downwardly toward the lower wall thereby releasing the filter so that it can be withdrawn from the inner end of the coupling. After the dirt filled bag is withdrawn from the filter chamber, 75 is in place over the opening for said filter chamber.

a new one is assembled by grasping the upper edge of the bottom and inserting the inlet 51''' over the end of the coupling as it is held collapsed by depressing the manual operator button 76. As soon as the inlet is in the plane of seating groove 47'''', the thumb piece is released allowing the coupling to expand against the edge of the filter opening. The end cap is then closed and locked, and the flexible hose is reconnected to socket 32'''.

While I have shown and described but three embodiments of my invention, it is to be understood that these embodiments are to be taken as illustrative only and not in a limiting sense. I do not wish to be limited to the particular structure shown and described but to include all equivalent variations except as limited by the scope of the claims.

I claim:

1. In combination with a tank type suction cleaner having a filter chamber provided with a large area inlet opening for the insertion and removal of a filter bag therethrough, a throw-away paper filter bag having a relatively small area inlet opening through a wall thereof, a resilient self-expanding tubular coupling carried by said cleaner having its axis extending in a direction crosswise of a wall of said filter chamber whereby means providing an air flow passage can be connected to the outer end thereof, means adjacent the opposite inner end of said coupling defining a narrow filter seating groove of a size and shape to seat and grip the rim edge of said filter inlet opening in an air tight manner, the wall of said resilient coupling being collapsible inwardly toward the axis of said coupling to reduce the cross sectional area thereof so that the filter inlet of said filter can be inserted over the end of the collapsed coupling until the plane of said inlet lies in the plane of said coupling seating groove whereby said coupling when allowed to expand under its own resiliency returns to its normal shape with the rim of said filter inlet seated in said groove and forming an airtight seal therewith.

2. A suction cleaner having a casing forming a filter bag housing, means providing an air inlet passage extending through the wall of said housing, means for detachably connecting a throw-away paper filter bag to said air inlet passage, means including a resilient tubular self-expanding coupling having an inner discharge end terminating within said filter chamber, means supporting said coupling so that at least one side thereof is free for depression inwardly toward the axis thereof to reduce its cross sectional area so that its said discharge end can be readily inserted into an inlet opening through a wall of said filter bag, means providing a narrow outwardly opening filter seating groove on the outer wall and adjacent the discharge end of said coupling, the bottom of said groove having substantially the same circumferential length and shape as that of said filter inlet opening whereby said coupling can be collapsed sufficiently for the discharge end thereof to be inserted readily into said filter inlet and then allowed to expand with the rim edge of the filter seated in said groove and forming an airtight seal therewith.

3. A suction cleaner as defined in claim 2 wherein said filter chamber housing has a large area opening through the wall thereof, a closure member for said opening, said air inlet passage means extending through said closure member, and said self-expanding filter coupling being located on the inner side of said closure member.

4. A suction cleaner as defined in claim 3 wherein said self-expanding filter coupling includes means for mounting the same directly on said closure member.

5. A suction cleaner as defined in claim 3 including means movably supported by the filter chamber housing for supporting said self-expanding filter coupling with said coupling in alignment with and seated against the end of said inlet passage means when the closure member is in place over the opening for said filter chamber.

6. A suction cleaner comprising a housing forming a filter chamber having a large area opening in the wall thereof normally covered by a closure member, said closure member having a passage therethrough forming a combined air inlet passage, and suction hose socket, a filter coupling support member movably supported on said casing inwardly of and adjacent said large area opening, a self-expanding resilient tubular filter coupling secured to said support member with its outer inlet end adapted to form an airtight joint with the end of said hose socket, the outer peripheral edge of the discharge end of said coupling having means thereon forming a narrow seating groove adapted to receive and form an airtight seal with the rim edges of the inlet opening through a side wall of an air pervious paper filter bag, and said filter coupling being readily collapsible lengthwise thereof to facilitate the assembly of said coupling into and disassembly from the inlet opening of a filter bag and being adapted to return to its normal expanded condition automatically as soon as the collapsing pressure applied thereto is removed.

7. A suction cleaner as defined in claim 6 wherein the discharge end of said self-expanding filter coupling is cut off on a plane at an angle to the axis of said coupling and wherein said filter seating groove lies in a plane generally parallel to the inclined discharge end thereof.

8. In combination with a filter bag housing comprising a chamber having a large area opening in one wall thereof to receive a filter bag, a closure member for said opening hinged to said housing near one edge of said opening, plate means hingedly connected to said casing inwardly of said closure member and arranged to swing between a closed position parallel to said opening and an open position outwardly away from said opening, a suction hose socket extending through and supported by said closure member, a resilient tubular self-expanding filter coupling supported intermediate the ends thereof along one edge of said plate means, and so positioned that the outer end thereof is in alignment with the inner end of said hose socket when said closure member is closed, a non-reusable paper filter bag within said filter chamber having a relatively small area inlet opening through the wall thereof, flange means projecting from the outer wall of said filter coupling adjacent the inner end thereof arranged to fit snugly against the inner and outer rim edges of said filter inlet opening to hold the same assembled to said filter coupling and the side walls of said filter coupling being collapsible inwardly toward the axis thereof to disengage the same from the filter bag so that the latter may be disconnected and removed from said coupling.

9. The combination defined in claim 8 wherein said filter bag has a tubular main body having pleats extending along the opposite sides thereof and a flat end lying generally normal to the side walls of said main body, said inlet opening being located in a non-pleated wall portion of said filter and at one end of said tubular body portion.

10. The combination defined in claim 9 wherein said inlet opening is formed in said flat end wall lying generally normal to the side walls of the tubular main body thereof.

11. A tank type suction cleaner comprising a tubular housing, means dividing said housing into a power driven air suction device compartment and a filter chamber, a large area opening in the wall of said filter chamber, a closure member normally closing said opening, said closure member having a suction hose socket seating therein opening into said filter chamber, means supporting a tubular filter coupling having an inlet adapted to lie in alignment with said hose socket when said closure member is in closed position and a discharge end projecting into said filter chamber, said filter coupling being formed of flexible resilient material normally expanded to the full diameter thereof but being collapsible inwardly lengthwise thereof to facilitate the assembly of the discharge end through an opening in the wall of a paper filter bag, flange means on the outer wall of said discharge end

5

adapted to closely embrace the inner and outer rims of a filter inlet opening to hold a filter assembly to said coupling and being disengageable therefrom by collapsing one side wall of said coupling toward the opposite wall thereof.

10

12. A tank type suction cleaner as defined in claim 11 including a paper filter bag therein made in the form of a grocery sack of the type having a flat bottom and inwardly extending pleats along the opposite sides thereof whereby the same can be folded flat until installed in the cleaner, said filter having an inlet opening in a flat wall thereof, relatively stiff means secured to the outer rim of said inlet opening having an extension from one side thereof of forming a finger piece by means of which said inlet opening may be guided into position over the discharge end of said filter coupling as the same is held collapsed.

15

13. A tank type suction cleaner as defined in claim 11 including manually operable means operatively associated with said filter coupling and operable when depressed to collapse one wall of said coupling toward the opposite wall thereof to facilitate the assembly and disassembly of a filter bag to and from said coupling.

20

14. A suction cleaner filter bag housing closed except for a large area inlet opening, a closure member normally seated across and closing said opening, means forming a suction hose socket supported by said closure and having an inner end opening into said filter chamber, means supporting an open ended tubular self-expanding filter coupling in alignment with the inner end of said hose socket, the outlet end of said coupling having a plurality of projections extending outwardly from the outer wall thereof and cooperating with one another to form a narrow seating groove of a width to snugly embrace the inner and outer rim of an inlet opening through a wall of a paper filter bag and to hold the same in place on the inner end of said coupling, one wall of said coupling being free to move radially inward toward the opposite wall of the coupling when pressure is applied thereto from the exterior of said coupling.

25

15. A suction cleaner filter chamber as defined in claim 14 including manually operable means movably carried by said closure member for collapsing said coupling, said means having one portion thereof normally lying closely adjacent the exterior of the said freely movable wall of said coupling and another portion accessible from the exterior of said closure member for operating the same, said manually operable means being operable when depressed to collapse said coupling.

30

16. A suction cleaner filter chamber for a dirt filter bag, one portion of said chamber having spaced apart inner and outer walls, provided with aligned air inlet openings, an open ended self-expanding tubular filter coupling extending through the opening in said inner wall and supported thereon intermediate the ends thereof, said coupling being formed of flexible resilient material and at least one wall thereof being free to move inwardly toward the opposite wall thereof, means on the exterior of the inner end of said coupling to embrace the inner and outer rims of a filter inlet opening through the wall of a paper filter when telescoped over the inner end of said coupling, the interior wall of the opposite inlet end of said coupling being adapted to receive and seat the end of a suction hose when the latter is telescoped thereinto through the opening in the outer of said filter chamber walls.

35

17. A suction cleaner filter chamber as defined in claim 16 including manually operable means for collapsing said filter coupling to facilitate the assembly of a filter bag to the inner end thereof, said manually operable means being movably supported on said filter chamber with one portion thereof adjacent the exterior of said freely movable wall of said coupling and the other end thereof extending to a point conveniently accessible to the operator.

40

18. A suction cleaner filter chamber having a large area opening for the insertion and removal of a filter bag, a self-expanding tubular filter coupling made of flexible resilient

material, means supporting said coupling intermediate the ends thereof, said means extending inwardly toward the axis of said filter chamber opening and hingedly supported from a point adjacent the rim of said opening whereby said coupling may be swung toward and away from the plane of said opening for convenience in inserting or removing a filter bag from said filter chamber, the inner end of said coupling having means for releasably holding a filter bag in place thereon, a closure member for said filter chamber opening having a suction hose socket extending therethrough and positioned to interfit telescopically with the outer end of said filter coupling when said closure member is in closed position.

19. A suction cleaner filter chamber as defined in claim 18 wherein said suction hose socket and the adjacent end of said filter coupling have complementary tapered walls and wherein said hose socket projects into the inlet end of said coupling and prevents the walls of the coupling from collapsing inwardly when said closure member is in closed position.
